FIG. 2.

W. W. JOHNSTON, Inventor

By Beall & Tenwick

Attorneys

UNITED STATES PATENT OFFICE.

WALTER W. JOHNSTON, OF GADSDEN, ALABAMA.

MOLD FOR CULVERTS.

1,244,214.

Specification of Letters Patent. Patented Oct. 23, 1917.

Application filed May 27, 1916. Serial No. 100,277.

To all whom it may concern:

Be it known that I, WALTER W. JOHNSTON, a citizen of the United States, residing at Gadsden, in the county of Etowah 5 and State of Alabama, have invented certain new and useful Improvements in Molds for Culverts; and I do hereby declare the following to be a full, clear, and exact description of the invention, such as will enable others skilled in the art to which it 10 appertains to make and use the same.

This invention relates to plastic apparatus, and more especially to the cores of pipe molds; and the object of the same is 15 to produce an improved structure for supporting the form or core over which the arch of a plastic culvert is made, and providing means for dropping this form after the arch has set and removing it longitudinally from the culvert for use at another place. Small culverts as under roadways or the like will be built by this apparatus when the latter is made in sections, from two to six being necessary for a culvert 20 under the ordinary roadway, according to the length of the sections and the width of the roadway. While these culverts are generally built before the fill is made to carry the road over the stream being arched, 25 it is quite possible to use my improved mold when forming a culvert in a tunnel; and accordingly I reserve all rights to the use of this invention in any way of which it is susceptible. In the following specification 30 I have described two working constructions as perhaps most practical of several types which my invention may take, and referring to the accompanying drawings:

Figure 1 is a cross section of a type of 40 my invention, and Fig. 2 is a section on the line 4—4 of Fig. 1.

The invention aims at the provision of a support which will sustain the upper part or shell of the form from the floor of the 45 culvert until the arch has set, after which the support can be collapsed by moving it radially toward the center of the form to permit the latter to drop, and then the form and its support can be removed for further 50 use. I have shown the form as nearly semi-circular over its top, but would not be limited at all in respect to the shape of the same; and obviously the sizes, proportions and materials of parts are not essential.

55 In the type of my invention shown, slats 21 are carried by ribs 22 which are braced at

intervals by transverse templets 23. In this type there is but a single shaft 30 mounted in bearings through the templets, and near each end it carries a wheel or disk 60 31 provided with holes 32 and into one of which a pin 33 may be passed for locking the wheel to the templet 23. Pivotal 65 mounted in certain of said holes as at 34 are two telescopic bars, each made up of a pair of rods or straps 35 which have perforated bodies lapping each other and connected by bolts 36, and it is obvious that when the shaft is turned its crank wheel 31 will move these bars as may be necessary. 70 At each end of the templet is a plate 25 having a horizontal slot 26 in which is mounted slidably a pin 27, and the numeral 28 designates a link having in its upper end a slot 29 loosely mounted on said pin. 75 The support for the form in this type of my invention is the strip or shim 38, herein shown as of channel iron interposed between the lowermost slat 24 and the sill 37, and so long as these strips are in place they 80 support the shell from the sill or sills as will be clear. Attached to each strip at each end thereof is an angle iron 45 to which the lower end of the link 28 is pivoted at 46, and to which the lower end of 85 one of the bars is pivoted at 47.

In the use of this type of my invention the sills are laid longitudinally of the culvert to be formed, the shaft is turned so that the wheels 31 cause the bars to swing 90 the strips 38 outward, and the shell is placed in position with its lower slats 24 resting upon said strips—the contour of the outer face of the shell being preserved by the outer faces of the strips and sills. 95 After the arch of the culvert has set, the pin 33 is removed and power is applied to the shaft 30 to turn it. This draws inward on the bars 35, and the pivotal connection 47 causes each strip 48 to swing first to the 100 dotted position shown at the left of Fig. 3. Meanwhile the link 28 moves upward as its slot 29 permits and the pin 27 moves inward as the slot 26 permits; but continual turning of the main shaft draws the swinging supports so far inward that they no longer sustain the lower slats 24 from the sills 37. The form is then tapped to disengage its cling from the arch, and it drops onto the sills and may be removed longitudinally from the finished culvert and used 105 elsewhere. 110

I have swinging supports which move inward from beneath the lowermost slats 24 but do not become disconnected from the mold; and in any form of my invention the mold is drawn longitudinally out of the finished culvert and used again. I avoid the necessity for shoring or for the use of wedges or jacks, and it is not necessary that any workman crawl or reach into the 10 form or the culvert. The desirability of making the sections of such size that they can be readily handled will be apparent.

What I claim is:

1. In a collapsible mold for culverts, etc., 15 a core - box with a rigid shell structure adapted to be placed in position upon a foundation, a crank shaft mounted longitudinally within and on the core - box, a pair of shims adjustable beneath the edges 20 of the shell structure, and adjustable connections between said shaft and the shims.
2. In a mold for culverts or the like, a collapsible core comprising a form for the arch, transverse braces for the form, longitudinally extending, inwardly movable supports positioned beneath the lower edges 25 of the form, and a shaft mounted in the braces having means connecting the supports and said shaft to withdraw the supports from engagement with the core by rotation of the shaft.
3. In a mold for culverts and the like, the combination with the core made in sections and including transverse templets near 30 its ends, and a pair of sills; of a shaft journaled through said templets, strips resting

on said sills beneath the edges of the core, wheels on said shaft, bars connecting crank pins in said wheels with said strips for drawing the latter inward over the sills, 40 and swinging connections between the strips and templets, for the purpose set forth.

4. In a mold for culverts and the like, the combination with the core made in sections and including transverse templets near 45 its ends, and a pair of sills; of a shaft journaled through said templets, strips resting on said sills beneath the edges of the core, wheels on said shaft, bars connecting crank pins in said wheels with said strips for 50 drawing the latter inward over the sills, a plate carried by each end of the templet and having a horizontal slot, a link pivoted to each strip and having a longitudinal slot, and a pin slidable in both slots and loosely 55 connecting the plate and link, for the purpose set forth.

5. In a mold for culverts and the like, the combination with an arch form having templets across its interior, a shaft journaled through the templets, wheels fast on said shaft and each having a pair of crank pins, and telescopic bars each pivoted at its inner end on one of said pins; of sills under the edges of the arch, a strip between 60 each sill and the edge of the arch above it, a swinging support between the strip and templets, and pivotal connections between the outer ends of the bars and strips, for 65 the purpose set forth.

In testimony whereof I affix my signature.

WALTER W. JOHNSTON.
